CLAIM

I claim the ornamental design for a lighting fixture, as shown and described.

DESCRIPTION

FIG. 1 is a perspective view of a lighting fixture showing our new design.

FIG. 2 is a front view of the lighting fixture shown in FIG. 1.

FIG. 3 is a back view of the lighting fixture shown in FIG. 1.

FIG. 4 is a right side view of the lighting fixture shown in FIG. 1.

FIG. 5 is a left side view of the lighting fixture shown in FIG. 1.

FIG. 6 is a top view of the lighting fixture shown in FIG. 1; and,

FIG. 7 is a bottom view of the lighting fixture shown in FIG. 1.

The elements shown in broken lines are included for the purpose of illustrating portions of the lighting fixture that form no part of the claimed design.

1 Claim, 7 Drawing Sheets(56)
